COMBINATION BED, TABLE, AND SOFA

Ben Spangler, Brooklyn, N. Y.

Application February 12, 1937, Serial No. 125,405

8 Claims. (Cl. 5—3)

This invention relates to combination furniture and has for its main object to provide a device of this type which may be used as a table, a bed or a sofa.

5 Other objects of this invention are: to provide a device as characterized hereinbefore which will be novel and simple in construction and operation, easy to manipulate and to change from one form to the other, and adapted to be manufactured on a large scale.

Still further objects of this invention will be apparent as the specification of the same proceeds.

In the drawings, forming a part of this specification and accompanying the same:

Fig. 1 is a semi-diagrammatic side elevation showing my device formed into a table, portions of the same having been removed to improve the clearness of the showing;

20 Fig. 2 is a partly sectional semi-diagrammatic side elevation showing my device transformed into a bed;

Fig. 3 is a semi-diagrammatic side elevation showing my device turned into a sofa;

25 Fig. 4 is a cross sectional elevation of my device when in the form of a bed, the section being taken on the line 4—4 of Fig. 2;

30 Fig. 5 is a fragmentary cross section of the lower middle portion of my device when in the shape of a table as shown in Fig. 1;

Figs. 6, 7, 8, 9, 10, and 11, show the elements and various positions in an adjustable hinge device used in my invention, while

35 Figs. 12, 13, and 14, are similar details of another hinge device used in my combination furniture;

Figs. 15 and 16 are details illustrating methods of securing the head and foot boards when my invention is used as a bed;

40 Fig. 17 is a fragmentary sectional detail on the line 17—17 of Fig. 4, illustrating the construction of a portion of the link mechanism designed to operate certain locking means in my device;

45 Figs. 18 and 19 are fragmentary detail views of an arm rest used when my device is formed into a sofa;

Fig. 20 is a fragmentary cross section on the line 20—20 of Fig. 1, showing the frame construction of a section of my furniture; and

50 Fig. 21 shows in a perspective view portions of the joint of a brace, taken apart.

Referring now to the drawings more closely by characters of reference, the numeral 20 indicates in general, the central supporting portion of my device passing transversely across the whole width thereof and having the two leg portions 21 and 22, an elevated middle portion 23 with a throughgoing hollowed out portion or recess 24 therein.

55 Hinged, as at 25 and 26, on the upper trans-

verse edges of the base 20 are the left hand and right hand intermediate sections of my device, generally indicated by the numerals 27 and 28, respectively, the left hand section 27 being composed of a base board 29, a front side board 30 and a rear side board 31, while the main elements of the right hand one are, similarly, a base board 32, a front board 33, and a rear board 34.

Hinged at the left hand end of the left intermediate portion 27, as by the hinge device generally indicated by the numeral 35, is a left hand end section, generally indicated by the numeral 36, of the same width and height as the intermediate section 27, adapted to form a section of a bed in continuation of said intermediate section 27, as will be understood and will be more fully explained hereinafter, having a base board 37, a front side board 38 and a rear side board 39, said left hand end section 36 being terminated by a wall 40 inside of which a second wall 41 is provided to form a pocket 42 (Figs. 1 and 2), said walls 40 and 41 being somewhat longer than the width of the section 36, so that said pocket 42 will also be longer than said width, the end 10 of said section 36 being shaped accordingly, as will be understood (Fig. 16), said pocket thus being adapted to receive the foot board of the bed when desired, as will be described presently.

At the right hand end of the right hand intermediate section 28 is hinged, by a device generally indicated by the numeral 43, a right hand end section generally indicated by 44, of similar, so to say trough like, construction as the other sections and being mainly composed of a base board 45, and front and rear boards 46 and 47, similarly located and arranged as the respective parts of the left hand end section 36.

Turning now particularly to Fig. 2, a plurality of springs, indicated by the numeral 48, is arranged over the base board 29 in the left hand intermediate section 27, to form therein a base for a usual bed, as will be understood, and similar pluralities of springs 49, 50, and 51 are further arranged in the sections 36, 28 and right hand end section 44, respectively. A fifth group or plurality of springs 52 is provided over the top plate 53 of the center support 20, so that the said five groups of springs provide a continuous spring base for a bed when my device is placed into the 50 form shown in Fig. 2, by means to be explained hereinafter.

A mattress 54, and possibly blankets or other bedding, may be placed over the said spring base 55 and permanently kept in my device, moving therewith when it is formed into a table or into a sofa, as will be understood.

The right hand end section 44 is terminated by an end wall 55 and an intermediate wall 56, form- 60

ing a pocket 57, similar to the pocket 42 for the left hand end section 36.

Hinged, as at 58, to the upper outer edge of the left hand end section 36 is a board 59, forming 5 the left hand leg of my device when it is used as a bed, and hinged to the upper edge of the right hand end section 44, as at 60, is a similar board 61, forming the right hand leg of the bed.

A board 62 is placed along the outer wall 40 of the left hand pocket 42 being kept in an upright position in said pocket by a pin or plug 63 (Figs. 2, 16, and 15) and by a toothed lower end 64, said end entering into an appropriate opening in the bottom 65 of the pocket 42, and, similarly, a board 66 is placed into the right hand pocket 57, secured therein in its upright position by a plug 67 and a toothed lower end 68, the respective boards 62 and 66 forming the foot and head boards of the bed, it being understood, that 20 the pocket 42 is somewhat deeper than the pocket 57 so that the foot board will be lower than the head board of my device, as it is usual in bed constructions.

When I desire to form my bed, mainly indicated 25 in Figs. 2 and 4, into a table, as best shown in Figs. 1 and 5, the left hand intermediate section 27 of my device will be raised upwardly into the vertical position shown in Fig. 1, and I provide a bolt or locking device, generally indicated by the 30 numeral 70, and operable by a pedal link mechanism, generally indicated by the numeral 71, (Figs. 4 and 5) to keep the same in said vertical position.

In said table formation of Fig. 1, the left hand 35 end section 36 will be permitted to drop into a horizontal position, rectangularly to the middle section 27, and then secured by the hinge device 35, to be explained hereinafter.

Similarly the right hand intermediate section 40 28 will be turned into an upright position and secured therein by the bolt device 71a and then the right hand end section 44 will be secured in a horizontal position through the appropriate arrangement of the hinge device 43.

45 The foot and head boards 62 and 66 will be placed on top of the device, as shown in Fig. 1, to form the top of the table, and they may be secured by the catch and hook devices 72 and 73, as will be understood.

50 In case a larger table is desired, the left hand foot board 59 is turned upwardly to form a left hand extension for the table and it may be kept in said position by a brace 74 comprising pivoted sections 74a and 74b or being of any suitable construction, well known in the art. In a similar manner, the right hand foot board 61 may be turned upwardly and secured in its position by the brace 75, while if no extension is desired, said foot boards 59 and 61 may be left in a downwardly depending position, indicated by the dot and dash lines in Fig. 1.

When I desire to shape my combination furniture into a sofa, (Fig. 3) the left hand intermediate section 27 will be raised into an upright 65 position, similar to that used for the table, while the right hand intermediate section 28 will be left in a horizontal position, as used when my device is formed into a bed, and the right hand end section 44 will be left in a rectangular position to the section 28, by the appropriate use of the hinge device 43, that is, in the same relative position as it was fixed for forming the right hand side of the table, and in the position of the sofa, as shown in Fig. 3, the said section 44 will 70 act as the outer leg for said sofa.

The left hand outer section 36, on the other hand will be further released by the hinge 35, and will be permitted to hang downwardly, as shown in Fig. 3, substantially in parallelism with the left hand intermediate section 27 and in this 5 position, it will form a portion of the back of the sofa.

It will be obvious and understood that the mattress 54, and the blankets and other bedding possibly placed thereon, will take part in all these 10 movements and will be folded, as the shape of the table, and of the sofa respectively, requires, as shown in Figs. 1 and 3.

Appropriate ornaments, draperies and the like 15 may be provided to conceal the exposed portions of these parts when forming the table or the sofa, while I may arrange at the outer end of the left hand end section a rolled up ornamental cover sheet 80, and similarly at the outer end of the right hand end section 44 a rolled up ornamental cover sheet 81, normally kept concealed in said rolled up position but adapted to be pulled out and draped over the left hand, and the right hand, half of the upper surface of the sofa respectively their ends having elements 80a and 81a being adapted to be secured in appropriate receiving devices 80b and 81b respectively, in the center curve of the sofa, and such securing and receiving devices may consist of snap fastener buttons and sockets, at 80a and 81a, and at 80b 30 and 81b, respectively.

When forming the sofa from my device, the right hand board 66 of the top of the table will be removed from its securing devices 72 and 73, and said board folded double, around a hinge 35 66a, and then secured on the back of the right hand end section 44, by any appropriate means, as shown in Fig. 3, while the right hand extension board 61 of the table will also be doubled around its center pivot 61a and in this position tucked 40 underneath said section 44, as also shown in Fig. 3.

The left hand table top board 62 will also be folded around its pivot 62a and then placed into the left hand pocket 42 of the left hand terminal 45 section 36, while the left hand extension board 59 will be folded double on its center pivot 59a, and in this position suspended at the outer end of the left hand terminal section 36, as shown in Fig. 3.

50 In this manner a highly ornamental and comfortable sofa may be formed from my bed or table.

The construction and operation of the locking bolts 70 and 71a used for the left hand and right hand intermediate sections of my device when 55 they are brought into upright positions may be explained by describing the same for the bolt 70, the construction and operation of bolt 71a being entirely identical.

Referring now to the bolt 70, a lateral member 60 90 is secured at about the center of the lower marginal portion of the base board 29 of the left hand intermediate section 27, and the bolt proper 91 may enter into an opening in said member 90 and thereby fix or lock the intermediate section 27 in its upright position, as best shown in Fig. 5. A spring 92 normally urges said bolt 91 into said locking position, the major portion of the bolt being slidably held and secured in the stationary base 20, as at 93 and 94. A pivoted 70 link member or lever 95 is hinged at the lower end 96 of the bolt 91, and a second pivoted lever 97 engages, in a yielding pivoted manner, through the pin and slot mechanism 98, the outer end of the lever 95, said lever 97 being operable by the 75

pedal 99, protruding from the side of the base 20.

When the pedal 99 is operated, the lever link mechanism will pull the bolt 91 in a downward direction against the spring 92, as will be obvious, 5 until the upper portion of the bolt 91 is freed from the member 90 thereby permitting a movement of the section 27 on the pivot 25.

The construction and operation of the hinge device 35 may be explained with the aid of Figs. 6 10 to 11, as follows:

On the left hand end section 36, is secured a left hand member 100 of said hinge, best shown in the perspective of Fig. 7, while a similar member 101 (Fig. 8) is secured on the left hand intermediate section 27.

The two pivot members have oppositely placed but otherwise identical rounded heads 100a and 101a, respectively, secured together by a center pin 102 around which they are rockable. Each 20 rounded head 100a and 101a has three holes or apertures, designated 103, 104, and 105, for the hinge member 100, and 103a, 104a, and 105a, for the hinge member 101. An appropriate plug or pin device 106 may be placed into a coaxially 25 placed pair of said holes thereby locking the hinge device in a desired position.

When it is desired to form the left hand side of a bed from the left hand side of my device, the hinge 35 will be placed into the position shown 30 in Figs. 6 and 9, and the plug 106 secured in the coaxial holes 103 and 103a; and when a table is formed of my device, said hinge device 35 will be placed into the position shown in Fig. 10, the holes in the member 100 being moved with 90 degrees 35 anti-clockwise in relation to the holes in the member 101, and the plug 106 may be placed in the now coaxial holes 103a and 104, and, finally, when the back of the sofa is formed from the left hand portion of my device, the hinge 35 will be placed in the position shown in Fig. 11, the plug 40 106 now locking the holes 105 and 103a.

The construction of the hinge device 43 is entirely similar to that of the hinge 35, as shown in Figs. 12, 13, and 14. Member 110 is secured on the intermediate section 28, while the counter part member 111 of it is secured on the section 44, having circular heads 110a and 111a respectively cooperating with each other in an identical manner to that of hinge 35, in this case, however, only two adjusting holes 113 and 114 are provided in the member 110, and two appropriately placed holes 113a and 114a in the member 111.

When it is desired to form the right hand part of the bed of these sections, they will be placed in the position shown in Fig. 14 and a plug 115 will be placed through the holes 114 and 114a, while when it is desired to form a table or a sofa, sections 28 and 44 will be placed at a right angle to one another, as shown in Fig. 12, and the plug 60 115 now will be placed through the holes 113 and 114a.

When forming a sofa out of my combination furniture, I may provide an arm rest for both sides of the same, as generally indicated at 120 in Figs. 65 3, 4, 18, and 19. The members 120 which are to be formed as arm rests at the two sides of the sofa normally are stored in the recess 124 of the base 20, as shown in Fig. 4, each of said members being composed of a board element 121 having a hollow space 122 therein, housing a spring pressed, 70 preferably sheet metal, catch plate 123. When it is desired to make an arm rest out of said members 121, the same will be pulled outwardly from the recess 24 until the outer end 124 of the catch member 123 will engage a slot 125 in the

bottom of said recess 24 near the opening thereof, as indicated in Fig. 18. In this position member 121 is standing upright along the side of the sofa, as shown in Figs. 3 and 18, and the suitably shaped and ornamented upper end 126 thereof may 5 serve as the arm rest proper, while a hinged portion 127 of it may be opened up and releasably secured in its horizontal position by any appropriate means well known in the art (not shown) to serve as an extension for the arm rest. 10

To further secure said arm rest, catch 128 may temporarily be hooked into the member 121, as shown in Figs. 3, 18, and 19.

Temporary catch devices 130 may be used to prevent the folding of the leg boards 59 and 61 15 when the same are used as legs for the bed or extensions for the table top, and similar hook devices 131 may be used for the boards 62 and 66 when they are used as foot and head boards for the bed, or as parts of the table top, and it will 20 also be understood that any suitable hook devices 132 may be used for temporarily securing the boards 59 and 61 when used as the legs of the bed.

While I have shown what I consider a preferred embodiment of my invention, I am aware of the fact that changes and variations may be made in the details of construction and combination, and I desire to reserve my rights to all such changes and variations that are within the spirit 30 of this specification and the scope of the claims hereunto appended.

What I claim as new, is:

1. In a combination furniture, having a central stationary base, a plurality of springs to form 35 parts of a spring base for a bed on said stationary base, a right hand and a left hand intermediate member, each having a base board and two side boards to form a trough like usual bed frame portion hinged at the right hand, and left hand, 40 sides respectively of said stationary base, a plurality of springs in each intermediate section to form further parts of a spring base for a bed; a right hand and a left hand outer member of similar construction to said intermediate members and hinged to the respective right hand and left hand outer ends of said intermediate members, 45 a right hand and left hand leg board hingedly secured to the right hand and left hand outer upper edges of the respective outer members releasable means to secure said legs in a vertical position on said outer members when desired and releasable means associated with said hinges between said members to lock said members in desired relative angular positions to one another, 55 said members being adapted to be placed into horizontal alignment with the base to form a bed, the intermediate members adapted to be swung into vertical positions, means to hold said intermediate members in such vertical positions, the 60 outer members adapted to extend and be held in horizontally aligned positions projecting outwardly from the upper ends of the intermediate members, whereby a table support is formed, one intermediate member adapted to be swung down 65 to horizontal position to form a seat with its associated outer member engaging the floor to form a leg for the seat.

2. In a combination furniture as set forth in claim 1, transverse pockets at the left hand and 70 right hand ends of the respective outer members, and upright head and foot boards for a bed removably secured in the respective pockets.

3. In a combination furniture as set forth in claim 1, said intermediate members being adapted 75

to be turned into upright positions, a pedal operated slidable bolt for each intermediate member in said base to secure the same in its upright position, said bolt normally being urged into a receiving element in the respective intermediate member but being adapted to be withdrawn therefrom by said pedal, said outer members being adapted to be turned into horizontal positions, at right angles to said intermediate members, when in upright positions and said means associated with the respective hinge devices being adapted to secure said outer members in said horizontal positions, said foot and head boards being adapted to be removed from said pockets and to be releasably secured over said upright and on said horizontally placed members, to form the top for a table formed of said furniture.

4. In a combination furniture as set forth in claim 1, said intermediate members being adapted to be turned into upright positions, a pedal operated slidable bolt for each intermediate member in said base to secure the same in its upright position, said bolt normally being urged into a receiving element in the respective intermediate member but being adapted to be withdrawn therefrom by said pedal, said outer members being adapted to be turned into horizontal positions, at right angles to said intermediate members, when in upright positions and said means associated with the respective hinge devices being adapted to secure said outer members in said horizontal positions, said foot and head boards being adapted to be removed from said pockets and to be releasably secured over said upright and on said horizontally placed members, to form the top for a table formed of said furniture; said leg boards being adapted to be turned into horizontal positions and secured therein, to form extensions for said table top.

40 5. In a combination furniture as set forth in claim 1, said left hand intermediate member being adapted to be placed in an upright position, a pedal operated slidable bolt in said base to secure said left intermediate member in said position, said bolt normally being urged into a receiving element in said left intermediate member, but being detailed to be withdrawn therefrom by said pedal, said left hand outer member being adapted to be turned in a substantially downward direction in parallelism with said upright left hand intermediate member, the respective hinge device being adapted to secure it in said position, said right hand outer member being adapted to be turned into a downward direction, at a right angle to said right hand intermediate member and to be secured in said position by the respective hinge device, and a mattress element covering the upper surfaces of all members and being adapted to bend to follow their respective horizontal, upright and downward positions when said horizontal furniture is shaped into a sofa.

65 6. In a combination furniture as set forth in claim 1, said left hand intermediate member being adapted to be placed in an upright position, a pedal operated slidable bolt in said base to secure said left intermediate member in said position, said bolt normally being urged into a receiving element in said left intermediate member, but being detailed to be withdrawn therefrom by said pedal, said left hand outer member being adapted to be turned in a substantially downward direction in parallelism with said upright left hand intermediate member, the respective hinge device being adapted to secure it

in said position, said right hand outer member being adapted to be turned into a downward direction, at a right angle to said right hand intermediate member and to be secured in said position by the respective hinge device, and a mattress element covering the upper surfaces of all members and being adapted to bend to follow their respective horizontal, upright and downward positions when said furniture is shaped into a sofa; said leg boards having intermediate pivots 10 and normally being secured against folding by releasable means, and means to secure them in a folded position on the respective outer surfaces of said outer members, and said foot and head boards also having intermediate pivots and normally being secured against folding by releasable means, but being folded, and one being adapted to be stored in the pocket of one of said outer members, while the other being adapted to be releasably secured on the end of the other 20 outer member, when forming said sofa.

7. In a combination furniture as set forth in claim 1, said left hand intermediate member being adapted to be placed in an upright position, a pedal operated slidable bolt in said base to 25 secure said left intermediate member in said position, said bolt normally being urged into a receiving element in said left intermediate member, but being detailed to be withdrawn therefrom by said pedal, said left hand outer member being adapted 30 to be turned in a substantially downward direction in parallelism with said upright left hand intermediate member, the respective hinge device being adapted to secure it in said position, said right hand outer member being adapted to be 35 turned into a downward direction, at a right angle to said right hand intermediate member and to be secured in said position by the respective hinge device, and a mattress element covering the upper surfaces of all members and being adapted to 40 bend to follow their respective horizontal, upright and downward positions when said furniture is shaped into a sofa, an open transverse recess in said stationary center base, a slidable board element normally stored in said recess but being 45 adapted to be pulled therefrom through its opening and turned into a vertical position along the side of said combination furniture, releasable means to secure said board in said vertical position, said board forming an arm rest for said sofa. 50

8. In a combination furniture as set forth in claim 1, said intermediate members being adapted to be turned into upright positions, a pedal operated device for locking each intermediate member to secure the same in its upright position, said outer members being adapted to be turned into horizontal positions at right angles to said upright intermediate members, and said means associated with the respective hinge devices being adapted to secure said outer members in said horizontal positions, said foot and head boards being adapted to be removed from said pockets and to be placed over said upright and on said horizontally placed members, to form the top for a table formed of said furniture, each of said locks comprising a bolt slidable in said stationary base, an element on the respective intermediate member normally being out of engagement with said bolt, but being adapted to be engaged by said bolt when said intermediate member is turned into an upright position, a spring normally urging said bolt into a locking position, and a link mechanism operated by said pedal to withdraw said bolt when desired. 70
